My invention relates to percussion or hammering tools in which a drill head is subjected to blows produced by an impact element and has particular reference to tools in which the impact element is under action of centrifugal force.

The object of my invention is to provide a percussion tool having two impact elements operating one after the other, thereby producing a rapid succession of blows against the end of a drill head.

My invention is more fully described in the accompanying specification and drawing in which—

Fig. 1 is a sectional elevational view of my tool;

Fig. 2 is a transverse sectional view of the same; and

Fig. 3 is an enlarged view of a rotating disc with the impact element.

The tool consists of a casing 1 with a suitable handle and a cover 2. The casing and the cover 20 are provided with recesses for ball bearings 3, supporting trunnions 4 extending from discs 8 and 9. The trunnion 4 of the disc 8 is connected to a flexible shaft 5 rotatively supported in a bushing 6 fitted in a central extension of the casing 1. The discs are provided with spiral guiding grooves 15 opposite each other, extending tangentially to a circle K near the periphery of the discs and curving toward the centers of the discs where the grooves almost merge into each other.

30 The grooves represent guiding channels for cylindrical impact elements 10, the latter being free to slide in the grooves toward their periphery by the action of centrifugal force. The discs 8 and 9 are joined together by bolts 7.

35 The casing has a tangential extension 14 with a bore for a drill head or similar tool 12. The latter has an enlargement on the end engaging an adjustable bushing 13 in the bore. An impact plunger 11 is placed in the bore on top of the drill head, the axis of the plunger passing tangentially to the circle K so that the impact elements 10 can strike the end of the plunger when the shaft is rotating. The impact throws the elements 10 back toward the center of the discs, the centrifugal force returning them immediately to the peripheral position. The force of the blows can be regulated by adjusting the position of the drill head and plunger, the adjustment being accomplished by shifting the position of the bushing 13.

40 With my construction it is possible to use two impact elements, thereby doubling the speed of the operation. The tangential arrangement of the peripheral portions of the grooves, while enabling the impact elements to deliver axial blows, increases the operating speed of the impact ele-

ments by adding the component of the velocity due to the centrifugal force to the angular velocity of the circle K.

I claim:

1. A percussion tool comprising a casing having a centrally positioned extension at the side, a shaft journaled in the extension adapted to be connected to a source of power, a plate in the casing attached to the inner end of the shaft, a second plate in the casing in a spaced parallel relation to the first plate, the plates having at their inner sides curved bottomed grooves opposite each other extending from the outer portions of the plates substantially to the axis of their rotation, cylindrical members slidably supported at their ends in the grooves, means to support the second plate on the first plate, said means extending between intermediate portions of the discs outside the grooves, a tubular tangential extension on the casing and a plunger slidably supported in the tangential extension, the cylindrical members being adapted to successively strike the inner end of the plunger when the shaft is rotated, the tangential extension being adapted to removably support a drilling tool in an operative contact with the plunger.

2. A percussion tool comprising a casing having a centrally positioned extension at the side, a shaft journaled in the extension adapted to be connected to a source of power, a plate in the casing attached to the inner end of the shaft, a second plate in the casing in a spaced parallel relation to the first plate, the plates having at their inner sides arc-like grooves opposite each other and extending from the peripheral portions of the plates substantially to their centers, straight cylindrical members slidably supported in the grooves and abutting by their ends the bottoms of the grooves, bolts attaching the second plate to the first plate and passing through the plates at points at the sides of the grooves, a tubular tangential extension on the casing and a plunger slidably supported in the tangential extension, the cylindrical members being adapted to successively strike the inner end of the plunger when the shaft is rotated, the tangential extension being adapted to removably support a drilling tool in an operative contact with the plunger.

3. A percussion tool comprising a casing having a centrally positioned extension at the side, a shaft journaled in the extension adapted to be connected to a source of power, a plate in the casing attached to the inner end of the shaft, a second plate in the casing in a spaced parallel relation to the first plate, the plates having at

their inner sides curved bottomed grooves opposite each other extending from the outer portions of the plates substantially to the axis of their rotation, cylindrical members slidably supported 5 at their ends in the grooves, means to support the second plate on the first plate, said means extending between intermediate portions of the discs outside the grooves, a tubular tangential extension on the casing, a plunger slidably supported in the tangential extension, the cylinder

drical members being adapted to successively strike the inner end of the plunger when the shaft is rotated, the tangential extension being adapted to removably support a drilling tool in an operative contact with the plunger, and means to 5 adjust the position of the tool and plunger in the tangential extension for regulating the force of blows of the cylindrical members against the plunger.

RICHARD VASARD. 10
